(No Model.)

2 Sheets—Sheet 1.

M. J. BEERS.

BATHING GARMENT.

No. 310,171.

Patented Jan. 6, 1885.

Fig. 1.

Witnesses.

H. E. Longe
A. F. Hayden.

Inventor.

Martha J. Beers.
J. Curtis, Atty.

(No Model.)

2 Sheets—Sheet 2.

M. J. BEERS.

BATHING GARMENT.

No. 310,171.

Patented Jan. 6, 1885.

Fig. 2.

Witnesses.

H. C. Longe

A. F. Hayden

Inventor.

Martha J. Beers.

J. Curtis, Atty.

UNITED STATES PATENT OFFICE.

MARTHA JANE BEERS, OF BOSTON, MASSACHUSETTS.

BATHING-GARMENT.

SPECIFICATION forming part of Letters Patent No. 310,171, dated January 6, 1885.

Application filed May 7, 1884. (No model.)

To all whom it may concern:

Be it known that I, MARTHA JANE BEERS, a citizen of the United States, residing at Boston, in the county of Suffolk and State of Massachusetts, have invented certain new and useful Improvements in Bathing-Garments; and I do hereby declare the following to be a full, clear, and exact description of the invention, such as will enable others skilled in the art to 10 which it appertains to make and use the same, reference being had to the accompanying drawings, and to letters or figures of reference marked thereon, which form a part of this specification.

15 This invention relates to improvements in bathing-garments; and it consists, essentially, in forming the body and skirt in one piece, while the legs are made separate but attached thereto, the whole when completed forming 20 an integral garment, to be more fully herein-after described.

The drawings accompanying this specification represent in Figure 1 the garment on the wearer, and Fig. 2 a front view of a bathing-garment embodying my invention.

25 In the drawings, A represents the entire finished article; but it will be noticed that this particular garment is cut and formed in a manner heretofore not generally adopted in 30 garments for similar purposes, as the body or waist B is formed integral with the skirt, that the weight may be borne more by the shoulders than by the hips. If by the latter alone in order to uphold the skirt and legs when 35 made separately from the waist, undue weight comes upon the hips, and it is necessary to secure the material composing the same very tightly together, which is a great objection where freedom of movement of the body is 40 required, as in bathing. This waist B is formed integral with the skirt C, while the legs D D are cut of the usual shape, and, in lieu of being an independent separable garment, are connected in the manner shown in the drawings 45 and integral therewith.

It will be seen that the waistband a of the legs D D is entire, and attached for about one-third or more of its length, b, and at the rear to the lower back portion of the body B, where 50 the skirt in ordinary cases joins the body of the garment. This manner of attaching the legs leaves the front flaps, c c, of the body B loose, open, and facilitates putting it on, and are to be buttoned closely together when the garment is in use. In addition I have provided the waistband a with a running tape or cord, d, for the purpose of gathering the loose portions or fullness of the waistband a nicely about the hips, and giving more form and better fit of the garment to the person of the 60 wearer, and I have done away with buttons and button-holes now generally in use.

Supposing the garment unbuttoned, the wearer who desires to put it on proceeds as follows: Having drawn on the legs D D first, 65 the arms are then inserted into the sleeves, and the cord d is pulled until the fullness of the waistband is overcome, and the size of the latter accommodates itself to the waist of the 70 wearer.

The advantage of this garment is the ease and facility with which the wearer puts it on and takes it off.

The objection of buttons on the leg portion D D of the garment is obviated by the 75 gathering-band d, and by attachment of the latter to the body B most of the weight is transferred from the hips to the shoulders, although the hips assume some of it, owing to the gathering of the waistband about them. 80 Moreover, there is no trouble in having the parts mislaid, lost, or used by some one else, as each garment is complete and entire in itself.

What I claim as new, and desire to secure 85 by Letters Patent, is—

1. A bathing-garment consisting solely of a body and skirt in one piece, in combination with the leg portion attached directly thereto at the waist of said piece forming the body 90 and skirt.

2. The combination of the body B and skirt C, in one piece, with the legs D D and the gathering-band d; said band being attached to said body, and serving to gather in the waist 95 of the leg portion of the garment.

In testimony whereof I affix my signature in presence of two witnesses.

MARTHA JANE BEERS.

Witnesses:

H. E. LODGE,
A. F. HAYDEN.